UNITED STATES PATENT OFFICE.

GEORGE HANISKO, OF YOUNGSTOWN, OHIO.

SEMAPHORE.

1,363,111.

Specification of Letters Patent. Patented Dec. 21, 1920.

Application filed July 22, 1920. Serial No. 398,131.

To all whom it may concern:

Be it known that I, GEORGE HANISKO, a citizen of Czechoslovakia, residing at Youngstown, in the county of Mahoning and State 5 of Ohio, have invented certain new and useful Improvements in Semaphores, of which the following is a specification.

This invention relates to certain new and useful improvements in semaphores and has 10 for its primary object to provide a semaphore arm that is pivotally mounted at its lower end upon a base plate and is capable of swinging in opposite directions.

A further object of the invention is to 15 provide a semaphore arm pivotally mounted at its lower end upon a supporting base plate with lock devices arranged in the path of swinging movement of the arm in either direction to control the movement thereof, the 20 invention also providing for an extensible semaphore arm with a lamp bracket secured to the head thereof.

With the above and other objects in view, the invention consists in the novel form, 25 combination and arrangement of parts hereinafter more fully described and shown in the accompanying drawings, wherein like reference characters indicate similar parts throughout the several views.

30 In the drawings,

Figure 1 is a side elevational view of a semaphore constructed in accordance with the present invention, the supporting tie for the same being partially broken away,

35 Fig. 2 is a vertical edge elevational view showing by arrow lines the laterally swinging directions of the semaphore,

Fig. 3 is a horizontal sectional view, partially through the semaphore post and the 40 supporting base plate showing the locking lever for the pivoted semaphore post,

Fig. 4 is a cross sectional view taken on line IV—IV of Fig. 3 showing the base strip for retaining the lower end of the 45 semaphore post in position,

Fig. 5 is a cross sectional view taken on line V—V of Fig. 3 showing the tensioned latch engaging the semaphore post positioning lever,

50 Fig. 6 is a detail sectional view taken on line VI—VI of Fig. 3 showing the semaphore post in lowered horizontal position, and

55 Fig. 7 is a perspective view of the positioning lever for the semaphore post.

In the accompanying drawing wherein is

illustrated one embodiment of the invention, the reference numeral 1 designates the mounting base for a pivoted semaphore post 2 carrying a semaphore arm 3 at the upper 60 end thereof and upon which a hook 4 is mounted for supporting the signal lamp 5 shown by dotted lines in Fig. 1.

The semaphore post structure will first be 65 described, the same being extensible and embodying a lower section 6 longitudinally slotted as at 7 to provide a guideway for the upper extension 8, vertically guided therein by the straps 9 and retained in its adjusted 70 position by the key 10 passing through registering openings formed in the base section 6 and the upper extension 8 as shown in Figs. 1 and 2. Any preferred type of semaphore arm 3 may be secured to the upper 75 end of the post 2, the arm 3 being detachable for this purpose.

As shown more clearly in Fig. 4, the mounting base 1 is provided with a raised central portion 11 having the lower face thereof cut away to provide a recess 12 that 80 is closed by the bottom strip 13 lying flush with the lower face of the mounting base plate 1 and secured in position by the screws 14. To provide for the side swinging of the semaphore post 2, the lower end of the lower 85 section 6 thereof is rounded as at 15 and carries bearings 16, the lower side of the end 15 engaging the upper face of the closure strip 13 while the bearings 16 engage the upper walls 17 of the recess 12. The 90 upper face of the raised central portion 11 as shown in Fig. 3 is transversely slotted as at 18 to permit the lateral pivoted swinging of the semaphore arm 2 as will at once be 95 obvious.

Means is associated with each side of the mounting base plate 1 and engages the semaphore post 2 to hold the same either vertically or horizontally positioned at either side of the base plate, such means including a 100 locking lever as shown in Fig. 7 by the reference numeral 19 having one end 20 thereof provided with a central opening 21 for mounting on the pivot pin 22 carried by the base plate 1, the end 20 of the lever being 105 received in the recess 23 in the raised central portion 11 while the opposite end 24 of the lever extends into the recess 25 arranged in the base plate 1 at the opposite side of the transverse passage 18. The intermediate 110 portion of the lever 19 is provided with a cross head 26 that is positioned in the trans-

verse opening 18, that portion of the lever 19 beneath the cross head 26 being cut away to provide an inverted V-shaped notch as illustrated in Fig. 7 affording a clearance for 5 the semaphore arm 2 when the same is in the horizontal position shown in Fig. 6. In order to retain the lever 19 in locked position, the end 24 thereof is provided with an end cut providing a hook 27 having a lower 10 beveled face 28 that slides over the upper beveled face 29 of the sliding latch 30 shown more clearly in Figs. 3 and 5, the latch 30 being slidably mounted in the horizontal recess 31 that is alined with the recess 25 and 15 containing a coil spring 32 engaging the inner end of the latch 30, thus normally forcing the latch in a direction for engagement with the lever 19. To manually retract the latch 30 from engagement with the 20 locking lever 19, an operating knob 33 is fixed to the latch 30 and slidably extends through the side slot 34 in the side wall of the base plate 1 and in communication with the recess 31. When the latch 30 is moved to a disengaging 25 position relative to the lever 19, the ring 35 secured in the opening 36 in the end 24 of the lever may be employed for shifting the lever upon its pivot pin 22 in the operation thereof.

30 As shown in Figs. 1 and 3, the base plate 1 is provided with spike receiving openings 37 for mounting the base plate upon a tie 38 or other support. When the semaphore post 2 is in the vertical position shown in 35 Figs. 1 and 2 and it being desired to lower the same to the horizontal position shown by full lines in Fig. 6, the desired lever 19 is released from engagement with the latch 30 by shifting the latch against the tension 40 of the spring 32 to free the same from the lever hook 27, after which the lever 19 is moved upon its pivot pin 22 to displace the cross head 26 from the transverse slot 18 and permit the side swinging movement of 45 the post 2. When the post is moved to its horizontal position, the same is of an area substantially to fill the lower end of the passage 18 whereupon the lever 19 is again lowered to its locked position with the head 50 20 overlying the arm 2 and with the hook 27 automatically engaging the latch 30 by the coöperating bevel faces 28 and 29. The semaphore arm 2 may be locked in a horizontal position on either side of the base 55 plate 1 and the same may also be locked in a vertical position between the spaced ends of the two cross heads 26 as shown in Fig. 3. The vertical or longitudinal adjustment of the post 2 is accomplished by the section 60 8 sliding in the section 6 and locked in its adjusted position by the key 10. The arm

3 may be employed for signaling during daylight, while during darkness a lamp or other luminant may be supported upon the hook 4 carried by the arm 3.

65

While there is herein shown and described the preferred embodiment of the invention, it is nevertheless to be understood that minor changes may be made in the same without departing from the spirit 70 and scope of the invention as hereinafter claimed.

What is claimed as new is:

1. A semaphore of the type described comprising a mounting base, a semaphore 75 post pivoted thereon, a lever pivoted at each side of the plate and engaging the post to hold the same either vertically or horizontally positioned, said base plate being transversely slotted at the pivot point 80 of the post, cross heads carried by the levers extending into said slot and engaging the sides of the post when the same is vertically positioned and overlying the post when horizontally positioned.

85

2. A semaphore of the type described comprising a mounting base, a semaphore post pivoted thereon, a lever pivoted at each side of the plate and engaging the post to hold the same either vertically or horizontally positioned, said base plate being transversely slotted at the pivot point of 90 the post, cross heads carried by the levers extending into said slot and engaging the sides of the post when the same is vertically positioned and overlying the post when horizontally positioned and locking means for the swinging ends of the levers.

95

3. A semaphore of the type described comprising a mounting base, a semaphore 100 post pivoted thereon, a lever pivoted at each side of the plate and engaging the post to hold the same either vertically or horizontally positioned, said base plate being transversely slotted at the pivot point of 105 the post, cross heads carried by the levers extending into said slot and engaging the sides of the post when the same is vertically positioned and overlying the post when horizontally positioned and tensioned 110 latches engaging the swinging ends of the levers to hold the same in locked position.

110

4. A semaphore of the type described comprising a mounting base plate, a semaphore post pivoted thereon and independently operating means arranged in the path of movement of the semaphore post coöperating therewith to hold the post either vertically or horizontally positioned.

115

In testimony whereof I affix my signature.

120

GEORGE HANISKO.
